(57) **CLAIM**

We claim the ornamental design for a vent mount, as shown and described.

DESCRIPTION

FIG. 1 is a front perspective view of a vent mount in accordance with our new design;

FIG. 2 is a rear perspective view of the vent mount of FIG. 1;

FIG. 3 is a front elevation view of the vent mount of FIG. 1;

FIG. 4 is a rear elevation view of the vent mount of FIG. 1; FIG. 5 is a right side elevation view of the vent mount of FIG. 1;

FIG. 6 is a left side elevation view of the vent mount of FIG. 1;

FIG. 7 is a top plan view of the vent mount of FIG. 1; and, FIG. 8 is a bottom plan view of the vent mount of FIG. 1. The broken lines depict portions of the vent mount that form no part of the claimed design.

1 Claim, 8 Drawing Sheets
